UNITED STATES PATENT OFFICE.

LEANDER J. WING, OF LEXINGTON, MASSACHUSETTS; MABEL WING CASTLE, OF LEXINGTON, MASSACHUSETTS, ADMINISTRATRIX OF SAID LEANDER J. WING, DECEASED.

ROTARY STEAM-ENGINE.

1,208,875.

Specification of Letters Patent.

Patented Dec. 19, 1916.

Application filed May 8, 1906, Serial No. 315,803. Renewed May 16, 1916. Serial No. 97,981.

To all whom it may concern:

Be it known that I, LEANDER J. WING, a citizen of the United States, residing at Lexington, in the county of Middlesex and 5 State of Massachusetts, have invented certain new and useful Improvements in Rotary Steam-Engines, of which the following is a specification.

My invention relates to an improvement 10 in rotary steam engines, of the annular and concentric type of cylinder, through which a piston revolves carrying the main shaft with it, the bore of the cylinder being circular in cross section, the piston being provided with self expanding packing rings, and the engine being further provided with 15 a revolving disk abutment, balanced and counterweighted and adapted to revolve at right angles across the piston path at a uniform speed with the piston, with facilities 20 for automatic cut off and expansion of steam, to insure the highest attainable degree of economy in fuel.

Designers and builders of the better type 25 of the reciprocating piston engine, have for some time realized the need of a higher piston speed, in order to secure the best possible effect of the steam and also to increase the efficiency of their engines, without 30 increasing the weight of metal composing them, or the cost of their production. The attempt to satisfactorily solve this problem, has resulted in securing a much greater speed of the main shaft, than was formerly 35 deemed safe or practicable, and has also involved many new problems as to steam compression, balancing of parts, &c., but the limitations that stand in the way of any successful attempt to greatly increase the 40 reciprocating movements in our most successful steam engines, are too well understood to require discussion, and it may be safely assumed that so far as a high rotative speed of the main shaft is concerned, 45 the prudent limit has been already reached, hence it would seem that the only available way to secure the desirable results of a higher piston speed, is to replace the present reciprocating piston by a revolving 50 piston, and thus secure the combination of a very rapid piston speed, with a moderately slow rotative speed of the main shaft.

In view of the foregoing consideration, the object of my invention is to provide

an engine of such construction and arrangement of parts as shall secure durability in the wearing parts, through ample surfaces coming in contact, through automatic adjustment for wear, and through automatic compensation for variation in the parts in moving contact, due to the different temperatures to which said parts are subjected, under a prolonged and variable service of the engine.

A further object is to provide an engine 65 of such construction and arrangement of parts as shall secure a flexible connection between the revolving disk abutment, and the revolving piston disk, thus avoiding any tendency to grinding or leakage, between 70 the parts in revolving contact by reason of a variation in their expansion.

A further object is to provide an engine 75 of such construction and arrangement of parts, as to allow the revolving disk abutment to be counterweighted or suspended over the piston disk while in operation, with the weight of the disk abutment so much reduced as to secure automatic adjustment between the two revolving parts, in spite of 80 a variation in the expansion of said revolving parts.

A further object is to provide an engine, 85 of such construction and arrangement of parts, as to allow the thrust of the steam within the annular cylinder, upon the abutment, to be taken upon ball bearings, in such a manner, that the proper operation of 90 said bearings, shall in no way interfere with the flexible connection between the two revolving parts before mentioned.

In the accompanying drawings: Figure 1. is a rear elevation of the engine. Fig. 2. is an end elevation, with the valve gearing, and shafts and gears for operating the abutment removed. Fig. 3. is a cross sectional view of the engine, on a line cutting the abutment shaft in its longitudinal center, the piston being shown in elevation, with the expandible ring L^o removed to show internal construction. Fig. 4. is a view in elevation of the outside of the cylinder and the abutment chamber. Fig. 5. is a view in elevation of the inside of the cylinder and the abutment chamber. Fig. 6. is a sectional view of the upper bearing for the vertical abutment shaft. Fig. 7. is a plan view of the same. Fig. 8. is an end elevation of

the bearings and supporting standard for the diagonal shaft. Fig. 9. is a front elevation of the same. Fig. 10. is a view in elevation of the inner face of the abutment chamber cover and rim. Fig. 11. is a side elevation of the same. Fig. 12. is a plan view of the gland for packing the inner end of the stuffing box, which packs around the elongated opening r^3 . Fig. 13. is the plan view of the gland for the outer end of the stuffing box, which packs around the shaft D'. Fig. 14. is a plan view of the movable stuffing box for the abutment shaft. Fig. 15. is a plan view showing the inner end of the abutment chamber cover, adapted to contain the flexible packing for the abutment shaft. Fig. 16. is a plan view of the inner face of the suspended abutment shaft bearing. Fig. 17. is a plan view of the rear face of the same. Fig. 18. is a cross sectional view of the same. Fig. 19. is an end view of the adjustable box bearing for the abutment shaft. Fig. 20. is a view in cross section of the flange for the piston. Fig. 21. is a longitudinal view of the same, in cross section. Fig. 22. is a view in elevation of the bolt for the piston. Fig. 23. is an outline view of the split eccentric ring for the piston. Fig. 24. is a view in outline of the outer split ring for the piston. Fig. 25. is a view in elevation of the piston disk, with outer packing ring, piston extension and balancing weight in position. Fig. 26. is a view in elevation of the split metal packing ring for the piston disk. Fig. 27. is a plan view in outline of the same. Fig. 28. is a plan view of the inner face of the expansible packing ring. Fig. 29. is a sectional view of the piston arm, with the expandable rings in position. Fig. 30. is a side elevation of the piston disk complete. Fig. 31 is a plan view of the double flanged packing ring surrounding the cylinder bore. Fig. 32. is an edge view of the same. Fig. 33. is a plan view of the outside of the radial ear of the piston arm, showing the devices for connecting the balancing weight with the piston rings. Fig. 34. is a plan view of the inner face of the same. Fig. 35. is an outline view, showing the connecting devices passing through the forward ear. Fig. 36. is an enlarged outline view of the adjusting device for the ball bearings and abutment. Fig. 37. is an enlarged top view of the same. Fig. 38. is a plan view of the revolving disk abutment, showing the cut away section, and the method for coring out on the opposite side of the disk to balance the same. Fig. 39. is an enlarged plan view of a section of the grooved steel ring, showing the balls located in the groove. Fig. 40. a view in outline of the bottom of the counterbalancing yoke. Fig. 41. is a plan view of the balancing weight for the piston. Fig. 42. is an edge view of

the same. Fig. 43. is a plan view of the pin for the balancing weight. Fig. 44. is an enlarged, detached view in cross section, of the abutment chamber cover, showing the packing device for the abutment shaft. Fig. 45. is an enlarged, detached view in side elevation, of the stuffing box for the abutment shaft. Fig. 46. is an enlarged plan view of the outer flanged end of the abutment chamber cover, showing the elongated circular opening in the center of its inner end, with the stuffing box extending up through it. Fig. 47. in an enlarged plan view of the ring r^3 . Fig. 48. is an enlarged view in side elevation of the gland R⁴.

In the drawings accompanying this specification, it will be seen that the main portion of the engine is formed of the two sections B. and B'. said sections extending vertically high enough to embrace within their compass the annular cylinder in their lower portion, and the abutment chamber in their upper. The inner connecting surfaces of the sections B. and B'. are formed with flanges E². and E³. extending the entire length of said sections, and when the inner connecting faces of said flanges E². and E³. are planed and scraped to a fit, they are adapted to be secured together rigidly, on a vertical line coincident with the line of the main shaft D. and at right angles to the line of the abutment shaft D'. thus forming a reliable connection between the two sections B. and B'. To avoid any displacement, or lack of perfect alinement when the two sections are detached and replaced, steady pins, (not shown) slightly tapered, are put through the flanges E². and E³. at suitable points, which secure perfect alinement. When thus placed in due position with each other, the two sections B. and B'. are rigidly held in position by substantial screw-threaded bolts, with nuts, passing through the flanges E². and E³. and holding them securely in position, against any displacement from the steam pressure within the annular cylinder or abutment chamber.

At the lower end of the flanges E². and E³. are formed connecting flanges B². and B³. which extend outwardly from the finished connecting faces of flanges E². and E³. at right angles thereto, to form a proper base or foot for the engine, by which it is secured to any desired foundation. The above mentioned base plate or foot formed by the flanges B². and B³. is also connected with sections B. and B'. of the cylinder and abutment chamber M. by two parallel flanges E⁴. and E⁵. which commencing at the outer end of the base plate or foot B². and B³. sweep inwardly and upwardly to the center of the cylinder, forming a part of its outer shell, and thence upwardly and outwardly to near the center of the abutment chamber, at its outer circular end, with

which it connects, thus forming a substantial support for the engine at its base, and giving additional strength to the central portion of the abutment chamber, against 5 any vibration or displacement thereof, by reason of the impact and pressure of the steam against the revolving disk abutment N. and its connecting devices, within the abutment chamber M. The parallel flanges 10 E⁴. and E⁵. are made wide and thin, as they are only required to take the pressure in one direction, therefore they do not add greatly to the weight of the engine.

In Fig. 2 it will be seen that the valve 15 cylinders I. and I'. upon the outer circle of the annular cylinder, near to its connection with the abutment chamber M. are provided with flanges I². and I³. at each end, to which the bearings I⁶. and I⁷. for the valve shafts 20 are rigidly secured. Extending from the valve cylinders I. and I'. to the annular cylinder, on each side of the same, are projections, I¹⁴. and I¹⁵. radial to the main shaft D. on the inside of which are located the 25 steam passages E⁸. and E⁹. which allow ingress and egress of steam to and from the bore F. of the annular cylinder. Extending outward from each side of the valve cylinders I. and I'. are the flanged steam pipes 30 I¹². and I¹³. which carry live steam to, and exhaust steam from the valve cylinders I. and I'. It will be further seen in Fig. 2. that at that portion of the cylinder which joins the abutment chamber M. there are 35 formed radial projections E⁸. and E⁹. surrounding the cylinder which are adapted to contain a finished groove O². upon the inside surrounding the bore F. fitted to hold the finished ring e. which packs the abutment N. around the bore F. while similar 40 projections E¹⁰. and E¹¹. are adapted to contain a cavity M². in which the flanges e². and e³. of the packing ring e are located. In 45 the center of the abutment chamber M. between the hub sections of the annular cylinder and the top, is situated within the abutment chamber the large cavity M². adapted to have the revolving disk abutment N. freely revolve therein, while on each side 50 of this enlarged central section the abutment chamber is made on a smaller circle and is adapted to contain therein, the suspended bearings N'. and N². Outside of 55 this reduced circular section the abutment chamber M. is made square, to contain within it, the box section of the suspended bearings N'. and N². and the adjusting devices by which the suspended bearings are kept in 60 perfect alinement, from the outside of the abutment chamber M. Still outside of the square section just mentioned, the abutment chamber M. is finished with another circular section, flanged upon its outer end, and adapted to contain within its inner circular 65 chamber M⁴. at one end, the packing device

which allows a vertical movement of the horizontal abutment shaft D'. without detriment to the proper packing of said shaft against any leakage of exhaust steam from the abutment chamber M. when the engine is 70 in operation. This end section also furnishes a substantial support for the upper bearing d. for the vertical supplemental abutment shaft D². while the other end of the abutment chamber is fitted with the 75 plain cover R. to avoid the escape of steam from the inside of the abutment chamber M. In the center of the abutment chamber M. see Figs. 2. and 4. above the smaller circular portion is formed a hollow projection m'. 80 having a flange at the top, adapted to receive within it the upper enlarged portion of the suspended bearings N'. and N². while fitted to this is a gland m². and m³. fitted to contain the adjusting screws m⁴. and m⁵. 85 Above this in Fig. 2. will be seen the adjusting yoke M⁸. provided with a plunger M⁹. screw-threaded at the top, to compress the coil spring M¹⁰. see Fig. 3. The screw-threaded bolts m⁴. and m⁵. which are secured to the upper enlarged ends of the suspended bearings N'. and N². after passing 90 through the stuffing boxes m². and m³. pass through the ears M¹². of the yoke M⁸. and are held in position therein, by screw-threaded nuts above and below said ears, by 95 which arrangement there is secured a flexible contact between the revolving disk abutment N. and the piston disk L⁹. in their revolving movement across each other. 100

In Fig. 5. in the center of the abutment chamber M. will be seen the circular cavity adapted to contain the disk section of the suspended bearing N'. and N². beyond which circular section is seen the oblong opening 105 into which the rear part of the disk section of the suspended bearing N'. and N². is movably fitted. The movement being vertical, and space is allowed sufficient to cover any expansion of metals in contact, while in 110 operation, due to maximum heat.

Figs. 16. 17. 18. and 19. show the details of the construction of the suspended bearings N'. and N². and Fig. 16. shows the front face of the disk n. with a finished steel ring n⁵. 115 fitted in a groove near its periphery, said steel ring being provided with a semicircular curved groove n¹⁹. in the center of the outer face of the ring n⁵. adapted to have hardened steel balls n⁶. snugly revolve therein to take 120 the pressure of steam against the abutment N. In the center of the disk n. is shown the inner end of the adjustable box n⁷. and n⁸. and the shaft D'. by which the abutment is 125 revolved. At the top of the disk n. is shown the enlarged projection n⁹. by which it is secured to the yoke M⁸. above and below the center of the disk n. are shown the screw threaded holes n¹⁸. by which it is bolted to the abutment N. when being put in position 130

1 within the abutment chamber M. see Fig. 3. Fig. 17. shows the rear face of the disk n. with the shell for the box bearing in the center, outside of which are shown the small 5 square cavities n¹⁰. adapted to receive the lip p'. of the adjusting lever p. by which the bearing N'. and N². are put in perfect adjustment from the outside of the cylinder. Fig. 18. is a view in cross section with the 10 box n⁷. and n⁸. in position, and the grooved ring n⁵. shown in cross-section. Fig. 19. shows the box n⁷. and n⁸. looking at the smaller end.

Fig. 3. shows that the cylinder bore F. is 15 located one-half on section B. and the other half on section B'. while the abutment N. is suspended directly over the central line which divides the two sections B. and B'. and it will be seen that the thrust upon the 20 abutment N. from the impact of the steam against it, is taken upon the ball bearings n⁶. n⁶. partly on the lower side of the shaft, where the pressure coincides with the direction of the steam pressure upon the abutment N. while the action is just the reverse 25 upon the upper side of the shaft, therefore it seems desirable that the curved groove n¹⁰. should be on as large a circle as possible, to keep the maximum pressure upon the 30 balls as small as possible.

Figs. 35. and 36. show, mostly in outline, the device for adjusting the suspended bearings N'. and N². in their contact with the balls, and through these with the revolving 35 disk abutment N. and the device consists of four substantial levers, p. located on each side of the abutment, said levers p. p. having a large hole near one end, and the other end formed with a lip p'. at one side to engage 40 the hole n¹⁰. in the rear face of the suspended bearing N'. and N². in such a manner as to cause the lever p. to be moved vertically when the bearing N'. and N². is so moved and to the same extent.

45 In Fig. 5. at each side of the central opening in the abutment chamber 2. are shown two deep narrow pockets s. s. one above the other, with a cored cavity between, said pockets s. s. adapted to contain loosely the 50 levers p. p. and to be movably supported therein. Near the end or bottom of the pockets s. s. a circular opening q. q. is cut through the metal intervening between the pockets s. s. and the outside, and a like hole 55 somewhat smaller in diameter is cut through from said pocket s. s. to the central opening in which the box bearing is located to allow of the introduction therein of a tightly fitting eccentric pin P. see Figs. 36. and 37. 60 by which a fine adjustment is imparted to the position of the suspended bearings N'. and N². and the abutment N. The flanged pin P. is finished in such a manner that the inner end p³. shall be on the same plane with 65 the outer end p². although of smaller diameter

70 while the central portion p⁴. is made eccentric to both, and is adapted to nicely fit within the openings in the lever p. The pin P. is further provided with a flange p. finished on both sides, with semicircular 75 grooves p⁷. p⁷. extending nearly around it, adapted to have threaded tap bolts p⁶. p⁶. pass through said grooves and secure the flanges rigidly in any desired position, while in the center of the flange is a square cavity p⁵. adapted to have fitted therein the end 80 of a wrench, by which the pin P. may be oscillated in either direction, when the tap bolts p⁶. p⁶. are loosened and the packing beneath the flange permits. In this manner a perfect adjustment of the internal and 85 movable members is easily accomplished.

In Fig. 3. it will be seen that long bolts of small size, with heads, are passed through the ears n¹¹. of the box bearings n⁷. and n⁸. 90 and through holes in the disk of the suspended bearing N'. and N². and are tightly screwed into the hub portion of the revolving abutment N. for two purposes, first to hold the different parts in proper position 95 when they are placed within the abutment chamber M. All of the parts being assembled are placed in position together, and when the two sections B. and B'. of the cylinder are rigidly secured together by 100 means of their connecting flanges E². and E³. the long bolts are removed and short bolts of larger size adapted to pass freely through the ears of the gland n¹². and engage screw threaded holes n¹³. in the box bearing n⁷. 105 and n⁸. by which the position of the gland n¹². is adjusted, all of which is done from the outer end of the abutment chamber M. when the covers R. and R'. are removed. A second reason for inserting the long bolts in 110 the position hereinbefore mentioned, is to enable the curved steel rings to be tightly held against the balls which revolve in the grooves of said steel rings and fill said 115 grooves, thus bringing the balls and grooves into perfect alinement, so that when the tapered glands of box bearings n⁷. and n⁸. are placed in position within the box n. these glands may be babbitted and thus the ball n⁶. the groove n⁵. and the abutment shaft D'. and the tapered gland will all be brought 120 into perfect alinement before they are put into their respective operative positions. It will thus be seen that the revolving abutment N. the abutment shaft D'. the suspended bearings N'. and N². with the box bearings n⁷. and n⁸. are all held in suspension within the abutment chamber M. and are adapted to allow such vertical movement 125 of these parts as may be necessary to maintain a flexible contact between the abutment N. and the periphery of the piston disk L. across which it revolves regardless of any expansion of the metal composing the parts in moving contact, by reason of a greater or 130

less degree of heat to which they are exposed, under the varying conditions which the engine is called upon to work in the service required of it. It will be remembered that only such a proportion of the weight of the abutment N. and its connections is allowed to bear upon the piston disk L. as shall be found necessary to secure a good wearing contact between these parts, 10 and this is easily regulated by the proper manipulation of the screw threaded plunger M⁹. at the top of the engine.

The abutment chamber cover R. for section B. of the engine is shown in cross section, in due position, in Fig. 3, and in end and side elevations in Figs. 10. and 11. and consists of a short plain cylinder, having a head r. at one end, and is formed with an outwardly extending flange r'. on the other end, by which, when said flange r'. is finished to fit therein, it is secured to the outer end of the abutment chamber M. by screw threaded tap bolts r². passing through the flange r'. into and through the flange m'. 25 formed upon the outer end of the abutment chamber M. and rigidly securing it thereto, its purpose being simply to close that end of the abutment chamber M. against any leakage of the exhaust steam from within the 30 abutment chamber, it being also easily removed, to admit of any desired adjustment of the box bearings n⁷. and n⁸. at that end of the abutment shaft D'. from the outside.

The abutment chamber cover R'. is shown 35 in position, in cross section, in Fig. 3, and is like the cover R. just described, except that in the closed end r. seen in Fig. 10. there is an elongated circular opening r³. in the cover R'. and upon each side of this opening r³. are parallel projections r⁴. and r⁵. extending outward, the inner edges of which and the space between are fitted to receive the upper finished face r⁷. of the flange r⁶. of the stuffing box R². which flange r⁶. is 40 adapted to have a vertical movement between the parallel projections r⁴. and r⁵. when the abutment shaft D'. is moved vertically by reason of the expansion of the abutment N. and the piston disk L. The stuffing box 45 R². is formed with two glands R³. Fig. 13. and R⁴. Fig. 12, both fitted to a screw threaded contact with the outside of the stuffing box R². The gland R⁴. is adapted to pack the elongated opening r³. against any 50 leakage of exhaust steam around the outside of the stuffing box R². while the gland R³. is fitted to pack around the shaft D'. inside the stuffing box R². and is screw threaded upon its outer ring to engage the 55 screw threads on the outside of the stuffing box R². The inside bottom of the cover R'. is finished to allow the gland R⁴. to fit tightly thereon.

The revolving disk abutment N. is shown 60 in cross section, in due position in Fig. 3.

and a plan view in outline is shown in Fig. 38. and it consists of a substantial disk provided with a wide short hub N⁴. in its center, one half on each side of the disk, with an opening in the center to allow the abutment shaft D'. to be firmly secured therein by a substantial feather, or other desirable means. At one side of the disk it is cut away to allow the piston G. to freely pass through it, when the piston G. and the abutment N. are 70 in motion. The cut-away section N⁵. is large enough to allow not only the piston rings G'. and G². to pass it freely but also to allow the balancing weight L⁵. and the piston extension L⁷. to do the same. On the opposite 75 side of the shaft D'. from the cut-away section N⁵. in the plate of the disk N. the metal is cored away upon the inside of the plate leaving a thickness of metal on each face of the plate sufficient to withstand the steam pressure upon the outside of the plate, when the pressure is at its maximum without bending or breaking under the strain, and to assist the reduced plates in sustaining said 80 pressure substantial studs h. h. h. are left in the cored part, the area so cored out being sufficient to offset the metal cored out of the plate and provide a means of balancing the abutment when in motion. The outer periphery of the disk is finished in a curve to 85 fit the curve of the piston disk L. so that the area of contact between the piston disk L. and the abutment N. shall in one direction equal the thickness of the abutment, and in the other direction the thickness of the piston disk, thus giving a very substantial surface for contact of the wearing parts. The broad hub n⁴. of the abutment N. is provided 90 with the same appliances for containing the balls as are to be seen in the front face of the suspended bearings N'. and N². being a 95 groove N⁶. finished in the hub n⁴. near its outer edge, and adapted to contain the grooved steel ring in which the balls are located, seen on an enlarged scale in Fig. 39. 100 By a careful study of the devices for adjusting the contact of the balls on each side of the hub n⁴. of the abutment N. it will be 105 seen that the whole pressure and impact of the steam against the abutment N. is taken 110 upon the balls n⁶. and in such a manner as in no wise to interfere with any small vertical movement of the abutment N. by reason of 115 any unusual expansion of the metals in moving contact, within the abutment chamber M. 120

In Fig. 5. there is shown a circular groove O². surrounding the bore F. adapted to have nicely fitted therein, the lower portion e'. of the double flanged packing ring e. see Figs. 31. and 32. while outside of it, and surrounding the groove O². is located a chamber M². adapted to loosely contain the flanges e². and e³. of the double flanged packing ring e. which packs the abutment N. around the bore F. Near the outer end of the flanges 125 130

e^2 . and e^3 . are located holes e^4 . and e^5 . through the flanges e^2 . and e^3 . adapted to receive therein, small bolts with square counter sunk heads, having check nuts on the other side of the flanges e^2 . and e^3 . to hold the bolts in place with springs (not shown) for holding the flanges e^2 . and e^3 . in contact with the abutment N. and outer chuck nuts, also not shown, on said bolts to control the position 10 of the packing flanges e^2 . and e^3 . from the outside of the cylinder.

In Fig. 25. is shown the piston disk L. complete, with the piston extension L⁷. the outer piston packing ring G'. and the balancing weight L⁵. in position, with the piston arm L⁸. shown in dotted lines beneath the expansible packing ring L⁹. In Fig. 2. these same parts are shown, except the outer expansible packing ring L⁹. which is removed to show the construction of the inner ring L⁹. and how the piston arm L⁸. is made to pass through it. The periphery of the expansible packing ring L⁹. of which there are two, is formed with inter-locking 25 segments, and beneath these segments is finished a deep groove L¹¹. adapted to snugly contain the soft metal split packing ring L¹². see Figs. 26. and 27. while beneath this groove L¹¹. are made pockets L¹⁴. adapted to contain steel coil springs (not shown) to press the packing rings L⁹. outwardly, and compensate for the wear upon its outer side surface. The split ring L¹². being made of softer metal than the parts surrounding it, 35 is more expansible under heat, and while its temperature is normal, it snugly fills the groove L¹¹. but not so tightly as to interfere with the outward pressure of the springs located in the pockets L¹⁴. As soon as steam is 40 introduced into the bore F. the greater expansibility of the ring L¹². causes it to fill the groove L¹¹. so full as to hold the rings L⁹. in a rigid position, as to any outward expansion, by which it will be seen that every 45 time the cylinder of the engine cools off, this device will automatically take up the wear on the piston disk L. in its contact with the inner surfaces of the piston disk cavity F².

Figs. 3. 25. and 29. show that the outer end 50 of the piston arm L⁸. is provided with outwardly extending radial ears L¹. and L². between the finished parallel faces of which are located the self expanding packing rings G'. and G². which with the ears L¹. and L². form 55 the piston G. In the center of the ears L¹. and L². is shown a hole l'. see Figs. 29. 33. 34. and 35. adapted to receive snugly the bolt Q. Fig. 22. while the flanged ring L³. Figs. 20. and 21. is fitted to fill the space between the parallel faces of the ears L¹. and L². around the center, and inclosing the bolt Q. which is of such length that when the flanged ring is in position, the bolt Q. will hold the parallel faces of the ears L¹. and 60 L². rigidly against the ends of the flanged 65

ring L³. with the packing rings G'. and G². outside of it, between said ears. The finished length of the flanged ring L³. is such as to permit some movement of the rings L¹. and L². radially or otherwise, and still remain steam tight, on account of which freedom of movement, when the piston is rapidly revolved within the cylinder, the ring G'. and G². will be liable to the effect of centrifugal force to such an extent as will wear 75 the ring G'. of the piston, G. or the bore F. of the cylinder more on the outer than the inside, and to counteract this effect, a balancing weight L⁵. is secured to the ear L². upon the outside of which is formed a radial projection having beveled sides which the weight L⁵. is adapted to fit upon having a radial movement thereon. By this arrangement the rings G'. and G². of the piston G. and the balancing weight, because they contain the same amount of metal, are subjected to the same degree of centrifugal force, hence if they are connected with each other by a balancing lever, in a proper manner, one will counterbalance the other, at whatever speed 80 they may be revolving.

It seems desirable that the device for connecting the rings G'. and G². with the balancing weight L⁵. should be such as to admit of the steam being applied to either side 95 of the revolving piston G. at will, and proper care should be taken to prevent the passage of live steam inside of the piston rings, G'. and G². whereby these rings might be unduly expanded, while in operation, creating 100 undue friction between the outside surface of the ring G'. and the inner finished surface of the bore F. To prevent this the radial ear L². is formed with a larger opening through it, beneath the opening l'. for 105 the bolt Q. and this opening l'. is screw-threaded to admit of the introduction therein, of a flanged bushing l. being tightly screw-threaded therein, from the outside, the hole l'. in the bushing l. is adapted to receive therein, the headed spindle l⁴. as far as the shoulder on said spindle will permit, while the head of the spindle l⁴. is turned at right angles to adapt it to bear upon the bottom part of the ring G². see Fig. 34. 110 The outer end of the spindle l⁴. is adapted to have fitted thereto, a small elongated cap l⁵. Fig. 33. having the same leverage from the center of the spindle l⁴. as the head of the same. When the weight L⁵. is placed 115 in position over the projection having beveled sides to keep it in place, it is of such form as to cover the small cap l⁵. without binding, and by inserting the screw-threaded pin l⁶. through the weight so that it will be pressed by the outer end of the elongated cap l⁵. the device is made complete. In Figs. 8. and 9. will be seen the standard and bearing B'. for the diagonal shaft D³. which connects the main shaft D. with the vertical 120 125 130

supplemental abutment shaft D². The finely adjustable main bearings B. are shown in Fig. 1.

In this engine the valves, and the devices for operating them are the same as those shown in my application filed April 27, 1904. Serial Number 205,169.

It will be understood that the abutment N. shown in these drawings is finished upon both faces, and is therefore adapted to revolve in either direction in accordance with whichever side of the piston the steam pressure is applied. In an engine designed to revolve in but one direction the inside cornering of the disk may be dispensed with, and the metal can be taken from the disk opposite the cut away section upon the under side of the same, to balance the abutment, and the second finished face may be omitted.

20 The abutment N. is caused to revolve at a uniform speed with the piston and main shaft D. by the use of the following gears: Secured to the main shaft D. near the inner end of the main bearing C. is a bevel gear

25 H. which impinges a like bevel gear H'. which is secured to the adjacent end of the diagonal shaft D³. and actuates the same, while the other end of the shaft D³. is provided with a miter gear H². adapted to connect with and revolve a like miter gear H³.

30 secured to the lower end of the vertical supplemental abutment shaft D². to which shaft at its upper end is secured a like miter gear H⁴. adapted to impinge and operate the like gear H⁵. secured to the horizontal abutment shaft D'. and since the gears are of uniform diameter the rotation of the piston and main shaft will be identical with the abutment shaft.

40 In Fig. 40. will be seen an outline plan view of the lower end of the yoke M⁸. showing its beveled connections with the projections on each side of the abutment chamber, by which any twisting of the yoke M⁸. is avoided.

Figs. 41. and 42. show the method by which the balancing weight L⁶. is secured to the ear L². in such a manner as to give it any desired radial movement.

50 In Figs. 33. and 34. it will be observed that the head of the spindle 7⁴. extends in an opposite direction for the elongated cap 7⁵. in order that a like pressure upon either may counterbalance the other.

55 Figs. 44. to 48. inclusive, are enlarged, detached views to more fully show the construction of the device for packing the abutment shaft D'. where it passes through the abutment chamber cover R'. Just above the flange r⁶. of the stuffing box R². on the outside thereof is formed a shoulder r⁸. of a height corresponding with the thickness of the finished inner head r. of the abutment chamber cover R'. which shoulder furnishes a substantial seat for the ring r⁹. to rest

upon, and also prevents the ring r⁹. from being too rigidly pressed against the inside finished face of the head r. of the abutment chamber cover R'. when the gland R⁴. is set in proper position to pack the connecting surfaces. The ring r⁹. is sufficiently large in diameter to cover the elongated circular opening r³. in the head r. and lap sufficiently over its sides to cover any vertical movement of the shaft D'. and stuffing 75 box R². due to the expansion of the abutment N. and the piston disk L. when in operation. By this arrangement it will be seen that the same packing which packs around the stuffing box R². where the ring 80 r⁹. is tightly fitted, also packs around the outer edge of the ring r⁹. against any leakage of the exhaust steam from the abutment chamber M. and in no wise interferes with the vertical movement of the abutment shaft 85 D'. The movement being small the packing so arranged should have great durability, with need of adjustment at long intervals of time.

In Fig. No. 31 I have shown the packing plate which is adapted to be pressed against the outer flat surfaces of the disk-abutment by springs (not shown) located in the adjacent metal of the cylinder. Said springs are adjustable from the outside. This plate 95 is adapted to fit into a groove surrounding the base within the abutment chamber and is provided with a hole in the center through which the piston passes; its form is somewhat segmental. The purpose of the segmental form is to provide a wearing surface, which rests upon the outer parallel face of the disk-abutment and is of such form as to equalize the wear between them, by increasing the area of the packing plate to a degree 100 corresponding with the increased speed of the surface of the abutment-disk as its periphery is approached. There are three elements which enter into this problem: The varying of the speed of the surface of the 105 disk and pressure. Now as the speed and pressure are fixed the wear must be equalized by a change in the area of one or more of the parts in moving contact and the desired effect is best reached by a modification of 110 the form of the wearing surface of the packing plate; this form is shown in Fig. 3. My method of balancing the rotating disk-abutment consists in removing some of the metal flat side of the disk, but always within 115 the periphery so that a wearing surface is always left at and near the periphery, enough being taken out to balance the cut-away part of the disk-abutment. This I term internally balancing the disk. 120

Having fully described my invention, what I claim as new and desire to secure by Letters Patent is:—

1. A rotary steam engine having an annular cylinder, with a continuous finished 130

bore that is circular in cross section, a piston disk carrying a self expanding piston on its periphery, rotatable therein, said disk rigidly secured to the main shaft which it actuates, a revolving disk abutment, having a cut-away section at one side of its disk, adapted to revolve at right angles across the bore of the cylinder, in an abutment chamber that cuts through the same at right angles to the piston path, means for connecting the shafts of the piston disk and abutment, whereby they shall revolve at a relative, uniform, rotative speed, means for maintaining a flexible connection between the piston disk and abutment, means connected with the abutment for taking the impact and pressure of the steam against the abutment upon ball bearings, with internal devices for automatic compensation for wear and expansion in the moving parts in contact, together with means for automatic cut-off and expansion of the steam within the cylinder, substantially as shown and described, and for the purposes herein set forth.

25 2. In a rotary engine, the combination with the cylinder, provided with a single steam inlet, and a single exhaust outlet, of a revolving disk abutment, internally balanced and counter-poised located between said inlet and exhaust openings, and a revolving piston rotatable within said cylinder, substantially as shown and described, and for the purposes herein set forth.

3. In a rotary engine, a revolving disk abutment, internally balanced and counter-poised, said abutment having a cut-away section at one side of its central hub, with means for revolving said disk at right angles across the bore of the cylinder and across the piston disk, substantially as shown and described, and for the purposes herein set forth.

4. In a rotary engine, the combination with the annular cylinder, having a bore that is circular in cross section, a revolving disk adapted to carry a piston around said bore, a balanced and counter-poised disk abutment, having a cut-away section on one side of said disk, of a deep circular chamber adapted to contain said disk abutment, arranged to cut across the bore of the cylinder at right angles, said abutment adapted to revolve freely in either direction across the piston path, substantially as shown and described, and for the purposes herein set forth.

5. In a rotary engine, the combination with the annular cylinder, the revolving piston disk carrying a piston, of a balanced and counter-poised disk abutment, the disk being finished on both surfaces, and adapted to be packed on one or both of said surfaces, and provided with a cut-away section in said disk and having a curved outer edge to snugly fit against the periphery of the piston

disk across which it revolves, substantially as shown and described, and for the purposes herein set forth.

6. In a rotary engine, the combination with the cylinder, the revolving piston disk, and the balanced and counter-poised disk abutment, having a cut-away section in said disk, and with one or more finished faces adapted to be packed, of a split metal ring located in a groove around the cylinder bore, said ring being formed with outwardly extending flanges on each side at the top of said ring, said flanges finished to pack against the finished faces of the disk, and being provided with springs beneath said flanges to hold it in easy contact with the same, substantially as shown and described, and for the purposes herein set forth.

7. In a rotary engine, an internally balanced and counter-poised disk abutment with a cut-away section on one side of the disk, substantially as shown and described, and for the purposes herein set forth.

8. In a rotary engine, the combination with the revolving piston disk, a piston located between radially extending ears thereon, a balancing weight secured to one ear, of a balancing spindle, fulcrumed in a flanged bushing rigidly fixed in the center of said ear said spindle having a head turned at right angles within the piston rings and an elongated cap secured to the other end, the former engaging the inside bottom of the inner piston ring, and the latter engaging the balancing weight, in such a manner that the centrifugal force exerted on the rings will be offset by a like force exerted upon the weight, substantially as shown and described, and for the purposes herein set forth.

9. In a rotary engine, a revolving, balanced and counter-poised disk abutment, arranged to revolve at right angles across the bore of the cylinder, and formed with a cut-away section on one side of the disk, of means connected with said abutment to insure a flexible contact between the curved periphery of said abutment, and the periphery of the piston disk across which it revolves, substantially as shown and described, and for the purposes herein set forth.

10. In a rotary engine, a balanced and counter-poised disk abutment, provided with means connected with said abutment, to insure a flexible contact between said disk and the revolving piston disk across which it moves, and devices connected with each hub of said abutment, whereby the thrust and pressure of the steam against the abutment will be taken upon ball bearings adapted to adjustably engage the hub of said disk, substantially as shown and described, and for the purposes herein set forth.

11. In a rotary engine, the balanced and

counter-poised disk abutment, having a cut-away section on one side of said disk, and provided with substantial hubs on each side of said disk, with enlarged diameter, to contain a groove near the periphery of said hubs, adapted to receive therein a hardened steel ring, having a curved groove in its center to which is nicely fitted the balls of the ball bearing adapted to freely revolve in said groove, with outside devices for adjusting their contact with said hubs, substantially as shown and described, and for the purposes herein set forth.

12. In a rotary engine the balanced and counter-poised disk abutment having a cut-away section on one side of said disk, with substantial hubs of enlarged diameter having devices therein adapted to receive and support the balls composing the ball bearings, of suspended abutment bearings, located within the abutment chamber on each of said enlarged hubs, said bearings fitted in their adjacent faces to support like devices for the balls as those in the hubs of said abutment, with means connected with said suspended bearings, to hold them in suspension over the bore of the cylinder and impart a flexible contact between the abutment and piston disk, substantially as shown and described, and for the purposes herein set forth.

13. In a rotary engine, the balanced and counter-poised disk abutment having a cut-away section on one side, ball bearings connected with its enlarged hubs, and suspended bearings located on each side of said disk, and adjustably connected therewith, of a double yoke having outwardly projecting ears on opposite sides, by which it is connected with the suspended bearings by means of substantial screw threaded bolts which pass through said ears and are secured therein, said yoke being provided with a plunger adapted to engage the stiff coil spring in the pocket in the top of the abutment chamber, and by means of the screw threaded contact between the plunger and yoke, any desired portion of the weight of the abutment and its connections may be taken upon the spring, substantially as shown and described, and for the purposes herein set forth.

14. A rotary engine formed of two main sections, each containing one half of the annular cylinder, and one half of the abutment chamber, the two sections being secured together through flanges formed on the inside of each section, on a vertical line coincident with the line of the main shaft, the lower portion containing the annular cylinder, and the upper portion forming the abutment chamber, each section being alike and interchangeable, the lower section being formed with a supporting base or feet, and the upper portion being adapted to contain the abutment, the abutment shaft, suspended bear-

ings and adjusting devices for the same, with means for revolving the abutment shaft by connections with the main shaft, and at the same rotative speed, substantially as shown and described, and for the purposes herein set forth.

15. In a rotary engine, the combination with an annular cylinder, a bore therein which is circular in cross section, a revolving piston disk carrying a piston in said bore, a balanced and counter-poised disk abutment suspended above said piston disk and adapted to revolve across it at right angles, said abutment being provided with ball bearings in its hub sections, with suspended bearings located opposite the outer faces of said hubs, adapted to support said ball bearings in position, of substantial adjusting levers fitted with a curved outer end on a circle equidistant from the center of the finished hole in the other end of said levers, said levers formed with an outward extending lip at one side, adapted to engage openings in the rear face of the suspended abutment bearing and to cause the levers to move vertically when the suspended bearing moves, and to the same extent, said lever being supported in a pocket by means of an eccentric flanged pin in such a manner that any desired adjustment of the lever may be effected from the outside by partly revolving the pin in either direction, substantially as shown and described, and for the purposes herein set forth.

16. In a rotary engine the combination with an annular cylinder, having a bore that is circular in cross section, a piston disk rotatable therein carrying a piston, a balanced and counter-poised disk abutment suspended above said piston disk and adapted to revolve across the same at right angles, said abutment being provided with a shaft by which it is supported and revolved, of adjustable box bearings located in the outer portion of the suspended bearings, and adapted to be adjusted to fit the shaft, when the abutment is held in position by the ball bearings, and so arranged and adjusted that the ball bearings upon the hub of the abutment, and the box bearings upon the abutment shaft, shall work in harmony to keep the abutment and shaft in perfect alinement regardless of any vertical movement thereof, due to the expansion of the revolving parts in contact, substantially as shown and described, and for the purposes herein set forth.

17. In a rotary engine, the combination with an annular cylinder, a bore within the same which is circular in cross section a revolving piston disk carrying a piston, a balanced and counter-poised disk abutment, having a cut-away section on one side, a shaft rigidly secured within the center of said abutment, to support and revolve the

same, within the abutment chamber, and having outward connection by gears and shafting with the main shaft by which it is revolved, of a stuffing box located near the outer reduced end of the abutment chamber, and secured to the inner end of the abutment chamber cover, upon which it has a free vertical movement, said packing box being fitted with two glands, having a screw-threaded connection with the outside of the stuffing box, whereby one gland packs around the opening in the abutment chamber cover, through which the stuffing box passes, and the other gland packs around the abutment shaft both allowing any desired vertical movement of the abutment shaft, substantially as shown and described, and for the purposes herein set forth.

18. In a rotary engine, formed of two interchangeable sections secured together on a vertical line coincident with the line of the main shaft, by finished connecting faces of flanges formed upon each section, said flanges connecting at the bottom of said sections with supporting flanges formed to extend outwardly therefrom at right angles thereto, and said connecting flanges being broadened as they approach the supporting flanges, to insure a substantial base for the support of the engine, on a line coincident with the line of the main shaft, substantially as shown and described, and for the purposes herein set forth.

19. In a rotary engine, formed of two interchangeable sections, each containing one half of the annular cylinder and the abutment chamber, said abutment chamber, (when the two sections are secured together by finished connecting flanges), being adapted to contain the disk abutment with the shaft extending outside the said abutment chamber, and connecting by shafts and gears with the main shaft which actuates it, said abutment chamber being reduced in size as it extends outwardly, and being strengthened in said outward portion, by two parallel flanges on each section connecting at the bottom of each section with the base plate or foot and extending upward to the sides of the cylinder, of which they form a part, thence extending upward to connect with the reduced outer end of the abutment chamber, whereby additional strength is imparted to the abutment chamber to enable it to withstand any strain upon the parts, by reason of the impact and pressure of the steam against the abutment, when in operation, substantially as shown and described, and for the purposes herein set forth.

20. In a rotary engine having a main shaft and an abutment shaft, the combination with the system of shafts and gears, connecting the main shaft with the abutment shaft, and imparting a continuous rotary motion thereto, of a combined gear cas-

ing and shaft bearing secured to the outer flange of the abutment chamber, and arranged to allow vertical movement of the shaft, without detriment to the proper operation of the connecting parts, substantially as shown and described, and for the purposes herein set forth.

21. In a rotary engine, a balancing yoke constructed with depending sections on opposite sides, with grooves formed upon the internal surfaces of said sections on opposite sides, with beveled sides and being adapted to slide freely upon outwardly extending projections located on opposite outsides of the abutment chamber, said depending sections being connected by adjustable rods with the suspended bearings which support each end of the abutment shaft, whereby each end of said shaft is given a uniform movement as to time, direction, and degree, substantially as shown and described, and for the purposes herein set forth.

22. In a rotary engine, a balancing yoke and plunger, a coil steel spring located in a socket formed in the upper part of the abutment chamber, and adapted to engage the lower face of said plunger, which is inserted adjustably in and through the center of said balancing yoke, whereby the pressure of the abutment upon the piston disk, across which it revolves, is externally controlled at will, substantially as shown and described, and for the purposes herein set forth.

23. In a rotary engine, having an annular cylinder provided with a bore that is circular in cross section, and a revolving piston adapted to revolve in said bore and connected by substantial devices with the main shaft, the combination of a revolving disk abutment, provided with a cut-away section in said disk near its periphery, and being internally cored out to balance against gravity and a stiff coil spring located at the top of the abutment chamber, and said abutment being suspended over the piston disk by devices that connect it with said stiff coil spring, whereby a flexible contact is maintained between said disks, adapted to counteract the expansion thereof, under any increased heat to which they may be exposed, substantially as shown and described, and for the purposes herein set forth.

24. In a rotary engine, a rotatable disk abutment having a cut away section as described upon one side of its axis of rotation, the other side of the disk having cored recessed chambers as shown, the outer finished walls over said recessed chamber, being supported by metal posts which engage each adjacent inner wall, and adapt them to withstand the steam impact without spring or displacement, whereby the disk is perfectly balanced, substantially as shown and described, and for the purposes herein set forth.

25. In a rotary engine, a rotating disk abutment having an enlarged hub, the ends of said hub having recesses for the reception of anti-friction balls, corresponding recesses made in the bearings, said bearings and anti-friction balls as described.
26. In a rotary engine, a piston carrying disk rigidly secured in position to revolve freely within the annular cylinder, and a rotating disk abutment, supported on suspended bearings, and adapted to have its periphery revolve transversely across the periphery of the piston carrying disk, with appliances connected with said suspended bearings, whereby a yieldable contact is maintained between said revolving disks, and their expansion under heat is automatically compensated for, without detriment to the proper operation of the engine, substantially as shown and described, and for the purposes herein set forth.
27. In a rotary engine, a rotating disk abutment, a piston carrier rotating in a plane at right angles to the plane of the disk abutment, the peripheries of said disks running in contact, the disk abutment supported on suspended bearings over the piston carrier in such a manner as that the two disks shall be kept in close revolving contact through the force of gravity acting upon said abutment, with devices connected with said suspended bearings whereby the force of gravity is partly diverted to the stiff coil spring, and the pressure between said disks is regulated at will, as and for the purposes herein set forth.
28. In a rotary engine, a rotatable disk abutment supported upon suspended bearings, and means for automatically varying the position of said bearings and abutment, substantially as shown and described, and for the purposes herein set forth.
29. In a rotary engine, a rotatable disk abutment, and yieldable means for varying the position of said abutment, substantially as shown and described, and for the purposes herein set forth.
30. In a rotary engine, a rotating disk abutment and a piston carrier rotating in planes at right angles to each other and having their peripheries working in contact, means for yieldingly holding said peripheries in contact, whereby the changes due to expansion and wear are compensated, and means for holding the said disk abutment laterally in proper position, substantially as shown and described, and for the purposes herein set forth.
31. In a rotary engine having an annular bore that is circular in cross section, a piston revolvable therein, a flat disk abutment having smooth flat sides against which the steam abuts on either side at will, pockets formed in the metal adjacent to the revolving abutment, solid wheels occupying said pockets,
- to engage the suspended bearings and hold them in exact lateral adjustment on opposite sides of said disk abutment, with outside appliances for adjusting the position of said wheels, substantially as shown and described, and for the purposes herein set forth.
32. In a rotary engine, a disk carrying a piston and a disk serving as an abutment, supported by suspended bearings, and taking the steam pressure on either flat side of said abutment, said sides being in parallel planes, the two disks adapted to rotate transversely across each other on their peripheries, means to effect automatic compensation for wear and for variation in expansion by reason of change in temperature due to varying loads carried by the engine, substantially as shown and described, and for the purposes herein set forth.
33. In a rotary engine having a rotary disk abutment rotating transversely across the piston path, and having parallel flat finished surfaces on each side, an elongated packing adapted to fit around the outside of the cylinder bore, and means operated from the outside whereby the pressure of the packing upon the abutment is controlled at will, substantially as shown and described, and for the purposes herein set forth.
34. In a rotary engine, having an annular cylinder the bore of which is circular in cross-section, said cylinder being provided with a cavity or circular chamber between the bore and the main shaft, in combination with a piston disk revolvable in said cavity, provided with a two part expansible packing ring, located on the periphery of the piston arm, with inter-locking segments formed on its curved periphery, steel coiled springs interposed between its two sections that hold their outward faces against the adjacent parallel walls of the circular cavity, and a soft metal split ring located in a deep groove formed on the inner faces of said two sections, just beneath the interlocking segments, whereby the difference in the expansion of the two metals under heat will tend to hold the expansible rings in any desired position of contact with the adjacent walls of the cavity, thereby securing automatic compensation for wear and a minimum degree of friction of the parts in contact, while in operation, substantially as shown and described, and for the purposes herein set forth.
35. In a rotary engine, having an annular bore that is circular in cross section, a piston that is rotatable therein, a piston disk cavity located between said bore and the chamber containing the hubs of the piston disk, said cavity having a finished face on each side, in combination with self-expanding rings adapted to fit snugly over the hub sections of the piston disk and joined in the center

thereof by inter-locking segments provided with internal devices that hold the outer faces of said rings in revolving contact with said finished faces of the piston disk cavity, 5 whereby the wear upon the parts in contact is automatically compensated for, substantially as shown and described, and for the purposes herein set forth.

36. In a rotary engine, having an annular bore that is circular in cross section, a piston 10 that is rotatable therein, a piston arm, a piston disk cavity having finished walls on opposite sides thereof, self-expanding rings surrounding the piston arm and engaging 15 the finished walls of the piston disk cavity, in combination with steel coil springs interposed between said expanding rings having interlocking segments on their periphery and adapted to press the same outwardly, and a 20 soft metal cut ring situated in a groove beneath said interlocking segments, whereby said expanding rings are rigidly held in any desired adjustment against said finished faces of said piston disk cavity, thus 25 effecting automatic compensation for wear between the parts in revolving contact, substantially as shown and described, and for the purposes herein set forth.

37. In a rotary engine, having an annular 30 cylinder provided with a bore that is circular in cross section, a piston rotatable therein, a piston disk containing a piston arm having radial ears formed on its outer end, and constituting the heads of the piston, one 35 or more piston rings movably secured between said heads, in combination with radial projections formed on the outside of said ears having beveled edges adapted to have movably secured thereto a balancing 40 weight, connected by internal devices with the piston, whereby the effect of centrifugal 45 force upon said piston is automatically neutralized, substantially as shown and described, and for the purposes herein set forth.

38. In a rotary engine, having an annular cylinder provided with a bore that is circular in cross section, a piston having piston 50 rings rotatable therein, and connected with the main shaft by a piston arm having radial ears formed on its outer end with projections formed on their outsides, upon one 55 of which ears is located a balancing weight, in combination with a balancing spindle 60 with a head on each end and fulcrumed in one of said radial ears and adapted to engage the balancing weight at one end of the spindle, and the piston rings at the other end and to press them in opposite directions, 65 whereby the piston is automatically freed from the effect of centrifugal force, substantially as shown and described, and for the purposes herein set forth.

39. In a rotary engine, having an annular 65 cylinder provided with a bore that is circu-

lar in cross section, a piston revolvable therein with substantial connections between said piston and the main shaft, a suspended disk abutment with a flat finished face on each side of said disk and formed with a cut-away 70 section near its periphery, in combination with a cored section of said abutment opposite said cut-away section adapted to reduce the weight of metal to equal the volume of said cut-away section, whereby the 75 said abutment is balanced against gravity, substantially as shown and described, and for the purposes herein set forth.

40. In a rotary engine, having an annular cylinder provided with a bore that is circular in cross section, a piston rotatable therein and located upon the periphery of a piston disk which connects it with the main shaft, of an internally balanced abutment disk suspended over said piston disk, across 80 which it revolves at right angles, the peripheral curve of each disk being adapted to fit snugly upon the other over the entire surface of contact, substantially as shown and described, and for the purposes herein 85 set forth.

41. In a rotary engine, formed with an annular cylinder having a bore that is circular in cross section, a two ring piston located between radial ears formed upon the outer end of the piston arm which connects the piston with the main shaft, said ears having radial projections formed on their outside, in combination with a piston extension rigidly secured to one of said ears and 90 revolved by said piston, whereby the clearance of the engine is reduced in volume equal to the cubic contents of said piston extension, at each revolution of the piston, substantially as shown and described, and for the 95 purposes herein set forth.

42. In a rotary engine, formed with an annular cylinder and having a bore that is circular in cross section, a revolvable piston disk carrying a piston and connecting the 100 same with the main shaft, a disk abutment yieldably suspended over said piston disk, and adapted to revolve across the same at right angles thereto, in combination with main shaft bearings formed with devices 115 that allow of their vertical adjustment, without other displacement, substantially as shown and described, and for the purposes herein set forth.

43. In a rotary engine, formed with an 120 annular cylinder having a bore that is circular in cross section, a two ring piston rotatable in said bore, a balanced disk abutment revolving in a slot across said piston disk at right angles, said piston having a 125 single outer, split packing ring wider than the slot in which the disk abutment revolves, whereby one side of the said outer piston ring will engage the hither end of the cylinder bore, before the other side of said outer 130

5. piston ring leaves the thither end of the cylinder bore, the piston is adapted to pass over said slot freely without jar or displacement, substantially as shown and described, and for the purposes herein set forth.
44. In a rotary engine, formed with an annular cylinder having a bore that is circular in cross section, a two ring piston carried by a piston arm rotatable in said bore, 10 of a piston disk connecting said piston with the main shaft, said disk being formed by expansible interlocking rings located upon the hub sections of the piston arm and covering the same, substantially as shown and 15 described, and for the purposes herein set forth.
45. In a rotary engine, having an annular cylinder provided with a bore that is circular in cross section, a piston that is rotatable 20 therein located between radial ears formed on the outer end of a piston arm, in combination with a double flanged ring secured between said ears, and a self expanding piston 25 inclosing said double flanged ring, substantially as shown and described, and for the purposes herein set forth.
46. In a rotary engine, having an annular cylinder provided with a bore that is circular in cross section, a revolving piston 30 carried by a piston disk having radial ears formed on its periphery, said ears having finished parallel faces, a double flanged ring secured between said ears and a two ring piston encircling said ring, of a single bolt 35 for securing said parts against displacement, substantially as shown and described, and for the purposes herein set forth.
47. In a rotary engine, having an annular cylinder with a bore that is circular in cross 40 section, a self-expanding piston rotatable therein, in combination with a yieldable, rotatable, and balanced disk abutment, substantially as shown and described, and for the purposes herein set forth.
48. In a rotary engine, having an annular cylinder provided with a bore that is circular in cross-section, a balanced disk abutment suspended between the adjacent ends 45 of said bore, the periphery of said abutment adapted to revolve transversely across the periphery of the piston disk arm, which carries the piston in said bore, in combination with suspended devices connected with said abutment for automatically varying the position 50 of the abutment, whereby the contact between the two disks is rendered flexible, and grinding or leakage is obviated, substantially as shown and described, and for the purposes herein set forth.
49. In a rotary engine, a balanced disk 55 abutment, rotatable therein, and yieldable means for varying the position of said abutment automatically, substantially as shown and described, and for the purposes herein set forth.

50. In a rotary engine, having an annular cylinder provided with a bore that is circular in cross section, a piston member movable therein, a flexibly suspended disk abutment co-operating with the piston member under the influence of gravity, and external means by which the weight of the abutment is regulated at will, substantially as shown and described, and for the purposes herein set forth. 70
51. In a rotary engine having an annular cylinder with a bore that is circular in cross section, a self expanding piston rotatable therein, said piston formed with two split rings, one within the other, and movably secured between radially extending ears 75 formed on the periphery of the piston arm, said ears forming the heads of the piston which is connected by a balancing lever with a sliding weight carried on one of said ears, whereby the centrifugal force exerted upon 80 said piston member, when in operation, is automatically neutralized by an equal force exerted in an opposite direction upon the said sliding weight, substantially as shown 85 and described and for the purposes herein set forth. 90
52. In a rotary engine, having an annular cylinder with a bore that is circular in cross-section, and provided with one disk for carrying a piston on its periphery, revoluble in said bore, and provided with another disk which serves as an abutment or revolving cylinder-head, the former rigidly secured in position on the main shaft and supported by 95 vertically adjustable main bearings, the latter disk suspended above the former in such a manner as to adapt it to revolve transversely across the former whereby a flexible contact between the peripheries of said disks is established and ample compensation afforded for an increase of their diameters due 100 to the expansion of the metal composing said disks by reason of any increased heat to which they are subjected in the operation of 105 said engine, substantially as shown and described, and for the purposes herein set forth. 110
53. In a rotary engine, having an annular cylinder provided with a bore that is circular in cross-section, a piston carried by a disk secured to the main shaft, and having expanding split packing rings revoluble in said bore, a revolving disk abutment with one or more cut-away sections in its periphery and adapted to freely revolve between the adjacent ends of said bore, of an elongated packing plate located in a cavity surrounding one or both of said adjacent ends of the bore, and adapted to be held in 115 flexible contact against the finished outer surface of said disk abutment by springs, said packing plate being formed of such segmental shape as to equalize the wear between it and the revolving disk, whereby the sur- 120 125 130

faces in contact are suitably packed against leakage and wear, substantially as shown and described, and for the purposes herein set forth.

5 54. In a rotary engine, having an annular cylinder provided with a bore that is circular in cross-section formed one half in each of the two sections composing the cylinder, which sections are rigidly secured together 10 through flanges formed thereon, having a circular cavity or chamber in the upper part of each section containing a revolving disk abutment, with one or more cut-away sections in its periphery, substantially as shown 15 and described, and for the purposes herein set forth.

55. In a rotary engine formed with an annular cylinder and provided with a bore that is circular in cross-section, and having an abutment chamber with square and circular sections cast integral therewith, of supporting flanges located on opposite outsides of said cylinder and extending downward to the cylinder bed to form substantial legs or supports for the cylinder and extending upward to connect with the square and circular sections of the abutment chamber to give additional strength thereto, thereby fitting it to withstand the sudden impact of steam upon the revolving disk abutment without vibration or displacement of parts, substantially as shown and described, and for the purposes herein set forth.

35 56. In a rotary engine having an annular cylinder with a bore that is circular in cross-section, said cylinder formed of two equal sections, each section forming one half of the circular bore, and one half of an abutment chamber, adapted to contain a revolving disk abutment with an elongated packing plate adjustably resting on each of the finished flat sides of said abutment, in combination with a recess or chamber formed 40 one half in each of said sections in the adjacent walls of the abutment chamber, adapted to contain the said elongated packing plate, with adjustable devices operated from the outside to control the pressure of 45 said packing plate upon the revolving disk abutment, substantially as shown and described, and for the purposes herein set forth.

57. In a rotary engine formed with an annular cylinder having a bore that is circular in cross-section, a piston carrier revolving a two ring piston in said bore, a revolving disk abutment suspended over the piston path, and engaging the periphery of the piston disk, and revolving within an abutment chamber, a packing plate located on each of the flat finished sides of said abutment, of a circular groove formed around the ends of the bore, of sufficient depth and width to contain the circular portions of the packing plate which fit closely around the ends of the outer finished wall of the said circular bore, the adjacent ends of the said circular portions of the packing plate being fitted to correspond with the walls of the piston disk cavity, whereby a uniform wear is insured through the operation of the self-expanding packing, located on the piston arm, substantially as shown and described, and for the purposes herein set forth.

58. In a rotary engine having an annular cylinder provided with a finished bore that is circular in cross-section said bore being formed one half on each of the two sections which when rigidly secured together form the complete cylinder and abutment chamber, the bottom ends of said bore being closely fitted together and forming a continuous bore, in the lower part thereof, while the upper ends of the bore are so far cut away on each section of the cylinder as to permit the disk abutment to be freely revolved between the adjacent ends of the bore, said abutment being provided with an elongated packing plate adaptably held upon the finished flat outer faces of the abutment, and fitted to pack upon the outer finished face of the end of the cylinder bore, and to provide ample space for the location of the grooves around the outer finished surfaces of the bore, wherein the circular portion of the elongated packing plate is located, substantially as shown and described, and for the purposes herein set forth.

In testimony whereof I have signed my name to this specification in the presence of two subscribing witnesses.

LEANDER J. WING.
